METHOD OF AND APPARATUS FOR FORM-
ING TWO-PLY FOLDED TAPEMilo C. Dodge, Auburn, N. Y., assignor to
Columbian Rope Company, Auburn, N. Y., a
corporation of New York

Application July 30, 1931. Serial No. 554,095

6 Claims. (Cl. 270—86)

My invention relates to a novel method and apparatus for making tape, and has to do, more particularly, with the manufacture of two-ply folded tape of narrower widths than heretofore 5 commercially possible.

It is the primary object of my invention to provide a method and apparatus by which two-ply folded tape of extreme narrow width may be commercially manufactured in any length.

10 It is an object of my invention to provide a method and apparatus by which narrow two-ply folded tape may be made in uniform width.

Another object of my invention is to provide an apparatus for making two-ply impregnated paper 15 tape which is simple, inexpensive, free from tendency to clog or jam, widely adjustable in all respects, and which may be easily threaded with the ribbon from which tape is to be formed.

Further objects and objects relating to details 20 and economies of construction and operation will definitely appear from the detailed description to follow. In one instance, I accomplish the objects of my invention by the means set forth in the following specification. My invention is 25 clearly defined and pointed out in the appended claims. A structure constituting a preferred embodiment of my invention is illustrated in the accompanying drawings forming a part of this specification, in which:

30 Figure 1 is a top view of apparatus constituting a preferred embodiment of my invention;

Fig. 2 is a vertical sectional view of the apparatus taken on the line 2—2 of Fig. 1;

Fig. 3 is a transverse sectional view of the apparatus taken on the line 3—3 of Fig. 2;

Fig. 4 is a horizontal sectional view of the apparatus taken on the line 4—4 of Fig. 2;

Fig. 5 is a sectional view taken on the line 5—5 of Fig. 2, showing the construction of the ribbon 40 guiding block;

Fig. 6 is a sectional view taken on the line 6—6 of Fig. 2, showing the construction of the tape folding block;

Fig. 7 is a perspective view of the tape folding 45 block, and

Fig. 8 is a sectional view taken on the line 8—8 of Fig. 2, showing the construction of the guide block through which the tape passes after being folded.

50 In the drawings, the same reference numerals refer to the same parts throughout the several views.

In general, my invention consists in first slightly creasing or scoring a narrow ribbon of flexible 55 material along a line exactly parallel to one edge

of the ribbon which line may or may not be its longitudinal center, depending upon whether the plies of the tape are or are not to be of identical width, subsequently folding over the portions separated by the crease or score, and flattening out the thus folded ribbon so that the tendency to unfold is eliminated. The apparatus comprises, broadly, a roll having a groove, a creasing wheel having a rib or edge which normally runs in the groove, a guide member for accurately guiding the ribbon with respect to the rib and groove, and a member having a slot through which the creased ribbon is passed, the slot having walls which converge in the direction in which the ribbon is drawn and which effect folding of the 70 ribbon on the line of the crease to provide two-ply folded tape.

Referring to the numbered parts of the drawings, the disclosed tape making apparatus constituting a preferred embodiment of my invention 75 comprises a base 10, standard 11, having a pair of bosses 12, between which a roll 14 is journaled on screws 13 by which lateral adjustment of said roll may be effected. Roll 14 is grooved at 15 and a creasing wheel 16 having a rib or edge 17 which runs in groove 15 is mounted in the standard 11. The mounting for the wheel 16 consists of a member 18 having a square stem portion 19 which is slidably received in a square aperture 20 in the upper portion of the standard 11. The lower 80 portion of the member 18 is provided with an aperture 21, a portion 21a of which is threaded and a portion 21b which is enlarged. A stud shaft 22 having a bearing portion 22a, a threaded portion 22b and a slotted head portion 22c is mounted in the aperture 21 of member 18, and carries upon its end 22b the creasing wheel 16. A washer 23 and a screw 24 threaded into the end of shaft 22 retains the wheel 16 upon the shaft. A similar screw 26 is threaded into the other end 85 of shaft 22 for a purpose later to be disclosed. For the purpose of urging the edge 17 of creasing wheel 16 into ribbon creasing engagement with the groove 15 of roll 14, a spring 27 is provided which bears upon the end of stem 19. A 90 housing 28 formed integral with the standard 11, a cover plate 29, and an adjusting screw 30, provide support and adjustment for the spring 27. A wheel lifting device consisting of a yoke 31, engaging the heads 24a and 26a of screws 24 and 26, and a handle 32 is fulcrumed upon the pin 33, which is attached to the standard 11. A receptacle 34 containing a quantity of impregnating fluid such as oil and dye is provided with a roller 25 beneath which the ribbon "A" is drawn 95 100 105 110

prior to the creasing thereof, so that a quantity of impregnating fluid is absorbed by the ribbon. A scraper blade 35 is provided for removing excess impregnating fluid from the ribbon 5 "A" as it leaves the receptacle to be creased by wheel 16 and groove 15. A guide member consisting of a notched block 36 and a cover plate 37 is detachably mounted upon the standard 11 by cap screws 38, thereby providing interchangeability with blocks 36 having notches of various widths, so that the same machine may be used with ribbon of various widths. Upon the other side of the standard and similarly mounted by cap screws 39 is a second block 40 which effects 10 folding of the ribbon after it has been slightly creased by the wheel 16 and roll 14. Block 40 has a vertical slot 41, the entrance end 41a of which is as wide as the slightly creased ribbon which leaves the wheel 16. The walls of the slot 20 41 converge in the direction in which the ribbon is drawn, so that the width of the slot adjacent its outlet end 41b is approximately equal to only twice the thickness of the ribbon, and the ribbon as it passes through the slot is folded to form 25 two-ply flat tape. A cover plate 42 pivoted at one end to the block 40 and having a hooked end 43 engageable with a screw 44 threaded in the block retains the ribbon in the slot, but may be swung aside to uncover the slot and facilitate 30 initial threading of the ribbon therethrough. The end of the base 10 opposite the receptacle 34 is elevated to substantially the level of slot 41 and a block 45 is held pressed thereagainst by means of a pair of cap screws 46 and springs 47 disposed 35 thereon. Block 45 has its underside horizontally notched to provide a guide slot 48 for the tape, and since the guide slot 48 is at right angles to slot 41, the tape is given a slight twist as it passes from slot 41 through slot 48.

40 From the above description of the apparatus, its operation should be clear. Ribbon "A" is led beneath roll 25, and is impregnated with fluid such as oil and dye, the excess fluid is removed by scraper blade 35, the ribbon passes 45 through guide block 36 which guides it with respect to the edge 17 of wheel 16 which presses it into groove 15 and forms a crease or score therein. The thus creased ribbon then passes through slot 41, is folded on its crease line, is given a quarter of a turn, passes through guide 50 slot 48 and may then be spooled in rolls by conventional apparatus (not shown). Two-ply folded kraft paper tape having a ply or plies as narrow as $\frac{3}{16}$ of an inch may thus be formed 55 accurately and at great speed. Such tape may be used for many purposes. Kraft paper tape $\frac{3}{16}$ of an inch in width is particularly useful for weaving into insulating fabric coverings for electrical conductors.

60 While I have disclosed a method and apparatus particularly well adapted for the manufacture of kraft paper tape of narrow width, it is to be distinctly understood that ribbon composed of other materials such as cloth, metal foil, paper, etc., may be similarly formed into multi-ply folded tape.

Likewise, while the disclosed apparatus embodying my invention is designed to form two-ply tape having plies of equal width, by the use 70 of guide blocks having slots eccentrically disposed with respect to the creasing wheel and grooved roll, the crease and fold may be made along a line other than the center line of the ribbon and the tape thus formed will have one 75 ply of greater width than the other ply. Such

tape has especial value for the formation of three-ply insulating wrappings upon electrical conductors. These and other changes within the scope of my invention will readily appear to one skilled in the art to which my invention pertains. I, therefore, claim my invention broadly as indicated by the appended claims. 80

What I claim is:

1. In an apparatus for making two-ply folded tape, means for providing a longitudinal crease in the ribbon from which the tape is to be formed, said means comprising a roll having a groove therein and a creasing wheel having an edge which runs in the groove of said roll, means for guiding said ribbon with respect to said creasing wheel, and a member having a slot therein which is aligned with the creasing wheel, the walls of said slot converging in the direction away from the wheel, and a cover plate for said slot for retaining the ribbon therein as it is being passed therethrough and folded, said plate being capable of movement to uncover said slot and facilitate initial threading of the ribbon therethrough. 85
2. In an apparatus for making two-ply folded tape, means for providing a longitudinal crease in the ribbon from which the tape is to be formed, said means comprising a roll having a groove therein and a creasing wheel having an edge which runs in the groove of said roll, means for guiding said ribbon with respect to said creasing wheel, a member having a slot therein which is aligned with the creasing wheel, the walls of said slot converging in the direction away from the wheel, and a second member having a slot disposed at right angles to the slot of the first member. 90
3. In an apparatus for making two-ply folded tape, a base, a receptacle on said base for holding impregnating fluid, ribbon immersing means including a roll journaled in said receptacle, a scraper blade for removing surplus impregnating fluid from said ribbon as it leaves said roll, means for providing a longitudinal crease in the ribbon, said means comprising a roll having a groove therein and a creasing wheel having an edge which runs in the groove of the first roll, means for guiding said ribbon with respect to said crease forming means, and a member having a slot therein which is aligned with the creasing wheel, the walls of said slot converging in the direction away from the rolls to fold the creased ribbon to provide two-ply tape. 100
4. In an apparatus for making two-ply tape, a base, ribbon impregnating means mounted on said base, a standard mounted upon said base, a grooved roll journaled upon said standard, an arm pivoted upon said standard, a creasing wheel journaled upon said arm and having an edge engageable with the groove of said other roll, means associated with said arm for normally urging same to maintain said edge in engagement with said groove, a handle attached to said arm whereby said arm may be swung to disengage the edge of said wheel from the groove of the roll, means for guiding said ribbon with respect to the edge of said wheel, and a member having a slot therein which is aligned with the edge of said wheel, said slot having walls which converge in the direction away from the rolls. 115
5. In an apparatus for making two-ply tape, a base, ribbon impregnating means mounted on said base, a standard mounted upon said base, a grooved roll journaled upon said standard, an arm pivoted upon said standard, a creasing wheel journaled upon said arm and having an edge 120

engageable with the groove of said other roll, means associated with said arm for normally urging same to maintain said edge in engagement with said groove, a handle attached to said 5 arm whereby said arm may be swung to disengage the edge of said wheel from the groove of the roll, means for guiding said ribbon with respect to the edge of said wheel, a member having a slot therein which is alined with the edge 10 of said wheel, said slot having walls which converge in the direction away from the rolls, and a cover plate for said slot for retaining the ribbon therein as it is being passed therethrough and folded, said plate being capable of movement 15 to uncover said slot and facilitate initial threading of the ribbon therethrough.

6. In an apparatus for the continuous formation of narrow two-ply tape, creasing means comprising a roll having an annular groove formed

in its surface and a creasing wheel having an edge which runs in said groove, means for directing flat ribbon stock tangentially between the surface of said roll and the edge of said wheel, said means including a guide member at the 80 entrant side of said creasing wheel and roll and having a shallow ribbon-directing slot of the same width as said ribbon and tangentially alined with respect to the surface of said roll, and means for longitudinally folding said ribbon as it leaves 85 said creasing wheel and roll to form two-ply flat tape, said means comprising a second member disposed at the other side of said creasing wheel and roll and having a slot in alinement with the slot of said first member, the width of which slot is equal to only twice the thickness of said ribbon and the depth of which is at least one-half the 90 width of said first-mentioned slot.
